UNITED STATES PATENT OFFICE.

WILLIS H. O'BRIEN AND DANIEL SIAKEL, OF CHICAGO, ILLINOIS; SAID O'BRIEN
ASSIGNOR TO SAID SIAKEL.

FILM-HOLDER.

1,837,614.

Specification of Letters Patent. Patented Apr. 20, 1920.

Application filed July 10, 1919. Serial No. 309,802.

To all whom it may concern:

Be it known that we, WILLIS H. O'BRIEN and DANIEL SIAKEL, both citizens of the United States, and residents of Chicago, 5 in the county of Cook and State of Illinois, have invented certain new and useful Improvements in Film-Holders, of which the following is a specification.

This invention relates in general to reels 10 or spools upon which strips of film, or the like, are adapted to be wound, and has more particular reference to the provision of a device for attaching the end of the film or strip to the reel so that the winding 15 operation can be begun.

In the handling of motion picture films which are wound successively from one reel onto another, both during the projection of the pictures and also during the rewinding 20 operations, it is essential to secure the initial end of the film to the reel in order that the winding operation may be begun. We are aware that various devices have been utilized 25 for securing the end of the film to the reel for this purpose, but all of these devices are awkward and unhandy to manipulate as it is necessary to insert the end of the film under some sort of a holder attached 30 to the wheel-hub, which necessitates introducing the hand between the flanges of the reel and attaching the end of the film to the holding device on the hub. Since the wheel flanges are only approximately 12 35 inches apart, and since these flanges are approximately 10 inches in diameter, it is manifest that to attach the end of the film to a holding device on the hub between the flanges is an awkward and difficult task.

One of the primary objects of our present 40 invention is to provide a holding device by which the film end can be secured to the reel hub quickly and conveniently and without necessity of reaching in between the flanges of the reel.

During the rewinding operation the film 45 is wound very rapidly from one reel onto another, and when the last of the film is unwound from a reel, the end must be released, or otherwise it will be torn off. Another object 50 of our invention, therefore, is to provide a holding device which will not only securely hold the end of the film during the winding operation but will automatically release the film when it is unwound from 55 the reel.

Other objects and advantages of our invention will be readily appreciated by those skilled in the art as the same is better understood by reference to the following description when considered in connection 60 with the accompanying drawing.

Referring to the drawings,—

Figure 1 is a transverse sectional view through a film holder embodying our invention. 65

Fig. 2 is a sectional view taken longitudinally of the hub; and

Fig. 3 is a detail view of the holding device.

By reference to the drawings, it will be 70 observed that the reel proper comprises a hub 5, usually made of sheet metal, and having a central core 6 shaped to fit over a spindle by which the reel is rotated in both the projecting and rewinding operations. At 75 its ends the hub is rigidly attached to the flanges 7 and 8 between which the film is wound upon the hub. The reel thus far described may be of any usual or preferred construction since our invention is applicable to any standard or even specially constructed reels. 80

Our novel holding device consists essentially of an L-shaped member comprising the elongated portion 9 and the portion 11 85 extending at right angles thereto. The portion 9 is pivotally attached to one of the flanges, preferably flange 8, near the marginal periphery thereof by means of a rivet 12 or other device by which the member is 90 pivotally secured to the flange. When thus mounted, the portion 11, when the main portion 9 is disposed radially of the reel, will lie in proximity to the hub 5, as shown in Figs. 1 and 2, and particularly the extremity thereof, since the angle between the portions 9 and 11 is slightly obtuse to bring the extremity of the portion 11 into clamping relation with the hub 5. The portion 11 is preferably made of resilient material and 100 near its juncture with the portion 9 it is of reduced width, as indicated by reference character 13, which permits the end of the portion 11 to be bent inwardly or outwardly to produce the requisite clamping effect. 105

When it is desirable to wind a film upon the reel, the holding device is first swung into position shown in dotted lines in Fig. 1. This movement may be effected without inserting the hand between the flanges of the 110

reel as the portion 9 can be grasped by the fingers from the outside of the reel through the opening 14 between the spokes 15 of the reel flange. A stud 16 projecting outwardly from the portion 9 limits the swinging movement of the holding device so that its end cannot assume a position outside the periphery of the reel. The end of the film 17 is now drawn across the hub 5 of the reel and when the extremity of the film closely approaches the hub 5, the holding device is swung from the position shown in dotted lines in Fig. 1 to the full line position shown in this figure, thus clamping the end of the film between the portion 11 of the holding device and the reel hub. The winding operation may now be performed, the successive convolutions of the film being disposed over the portion 11 of the holding device which does not interfere in any way with the winding or unwinding operations.

It will be observed that the film is held by a clamping action between the portion 11 of the holding device and the hub 5 of the reel, but there is no possible locking of the film since the parts are so proportioned that the holding device may swing in either direction from the full line position illustrated in Fig. 1. To facilitate this swinging movement, the portion 11 is curved transversely, as will be evident from Fig. 1. The clamping effect upon the film may be regulated by slightly bending the portion 11 of the holding device so as to increase or decrease its pressure against the reel hub as required.

When in unwinding the film from the reel, which unwinding is done very rapidly by a swiftly running motor, if the film end were fixedly secured to the reel, it would be torn off when the end was reached, unless the rewinding operation were slowed down so that the operator could manually remove or release the film end from the reel when the film was nearly unwound. With our device, however, the rewinding can be continued full speed and when the end of the film is reached, the pull exerted upon the film will withdraw it automatically from the reel, since the holding device will swing to release the film when the pull thereon becomes excessive. This release, when the parts are properly adjusted, will take place under a tension less than the tensile strength of the film, so that no tearing or injury to the film is liable to occur.

It is believed that our invention and many of its advantages will be understood and ap-

preciated from the foregoing without further description, and while we have shown and described one preferred embodiment 60 thereof, it is manifest that the details of construction are capable of considerable modification without departing from the spirit of the invention as set forth in the following claims.

We claim:

1. A film holder comprising a reel consisting of a smooth hub provided at each end with a radial flange, and a clamping device pivoted to one of said flanges near the 70 margin thereof and adapted when swung into radial position to releasably clamp a film to the hub of said reel.

2. A film holder comprising a reel consisting of a pair of parallel flanges united 75 by a central hub, and a holding device comprising an L-shaped member pivotally mounted on one of said flanges near the circumferential margin thereof and having a portion projecting in proximity to said 80 reel-hub substantially parallel to the axis thereof to yieldably clamp a film between said device and said hub.

3. A film holder comprising a reel consisting of a hub and a pair of flanges, and 85 a holding device consisting of an L-shaped member pivoted at one end to one of said flanges and having a portion extending substantially parallel with and yieldingly urged toward said reel hub to yieldably and re- 90 leasesably clamp a film end to said hub.

4. A film holder comprising a reel consisting of a cylindrical hub, and a pair of flanges, and a holding device pivoted to one 95 of said flanges remote from said hub, comprising a portion movable about said pivot in a path parallel with said flanges past and away from said hub in either direction and adapted when disposed tangentially to said hub to yieldingly clamp a film between said 100 portion and periphery of said hub.

5. A film holder comprising a reel consisting of a cylindrical hub and a pair of flanges, and an L-shaped holding device, one branch of which is pivoted at its outer end 105 to one of said flanges and the other branch of which swings in a path tangent to the perimeter of said hub so that a strip of film disposed on said hub is yieldingly clamped between said branch and said hub as the device approaches said hub in its swinging movement.

WILLIS H. O'BRIEN.
DANIEL SIAKEL.
